CLOCK OR SIMILAR ARTICLE

Theodore G. Dahir, Stratford, Conn., assignor to
General Electric Company

Filed Mar. 11, 1971, Ser. No. 123,482

Term of patent 3½ years

Int. Cl. D10—01

U.S. Cl. D42—7

*Fig. 2.**Fig. 1.*Fig. 3.

Fig. 4.

FIG. 1 is a front elevational view of a clock embodying my new design;

FIG. 2 is a top plan view thereof;

FIG. 3 is a front perspective view thereof with a portion of the ornamentation around the clock face frame being omitted for convenience of illustration;

FIG. 4 is a bottom plan view thereof;

FIG. 5 is a rear elevational view thereof; and

FIG. 6 is a side elevational view thereof.

I claim:

The ornamental design for a clock or similar article, as shown and described.
